UNITED STATES PATENT OFFICE.

VICTOR O. STROBEL, OF ALLEGHENY, PENNSYLVANIA.

HOT-BLAST OVEN.

SPECIFICATION forming part of Letters Patent No. 340,163, dated April 20, 1886.

Application filed February 5, 1885. Serial No. 154,989. (No model.)

To all whom it may concern:

Be it known that I, VICTOR O. STROBEL, of Allegheny, Allegheny county, Pennsylvania, have invented certain new and useful Improvements 5 in Hot-Blast Stoves, of which the following is a specification.

This invention pertains to improvements in fire-brick regenerative hot-blast stoves; and the improvements will be understood from the 10 following description, taken in connection with the accompanying drawings, in which—

Figure 1 is a vertical section, on line 6, of a hot-blast stove illustrating my improvements; Fig. 2, a horizontal section on line 1; Fig. 3, 15 a horizontal section on line 2; Fig. 4, a horizontal section on line 3; Fig. 5, a horizontal section on line 4; Fig. 6, a vertical section of a portion of the regenerator taken upon line 5; Fig. 7, a plan of the chimney-nozzle; Figs. 20 8 and 9, vertical sections of the chimney and hot-blast valves; Fig. 10, a vertical section, same plane as Fig. 1, exhibiting the regenerator in subdivided form, and showing the scraping device in position; Fig. 11, a horizontal section, lines 7 and 8, of the subdivided 25 regenerator, and Fig. 12 an elevation of the fulcrum-roller for the jet-pipe.

In the drawings, A represents the combustion-chamber of the stove; B, downtake-flues 30 of the regenerator; C, uptake-flues of the regenerator, consisting of rectangular flues formed by chord and ordinate walls; D, the chimney-connection; E, a pipe projecting outward from the stove at the base of the combustion-chamber; F, the gas-valve; G, the gas-pipe leading into the pipe E; H, the opening 35 of pipe E into the combustion-chamber, serving as an inlet for the gas and as the outlet for the hot blast; I, an opening through the stove-wall at the foot of the combustion-chamber and directly beneath the opening H; J, a valve-seathed to the opening I; K, a screw-valve fitted to this hinged seat; L, the hot-blast valve; M, a flue leading from the combustion-chamber at a point above the level of the opening H into the chamber at the foot of the regenerator uptake; N, a jet-pipe inserted through an opening in the stove-wall at the top of the combustion-chamber; O, a swiveling fulcrum 45 journaled in the sill of said opening and supporting the jet-pipe; P, arches at the foot of

the regenerator; Q, lintels over these arches; R, a separating wall reaching from the top of the stove downward and dividing the regenerator into a downtake and an uptake; S, the 55 chimney-opening in the brick roof of the stove; T, the upwardly-projecting nozzle of this opening; U, the cold-blast valve; V, the chimney-valve seat; W, the gate portion of the valve; X, an opening in the stove-wall at 60 the foot of the chamber below the regenerator; Y, the segmental bricks of which the chimney-nozzle is constructed; Z, the margin bricks of the chimney-opening in the brick roof of the stove; a, inlets from the atmosphere to the 65 cooling-cavities of the valve-seats; b, cooling-air outlet from said cavities to the chimney; c, pipe connecting such outlet of the hot-blast valve with the chimney; d, cooling-air inlets through the hollow stems of the valves for 70 chimney and hot-blast; e, aperture leading from the hollow of the chimney-valve to the chimney; f, pipe connecting the hollow of the hot-blast valve with the chimney; g, outlet portion of the hollow stem of the chimney- 75 valve; h, sheave and hand-crank on the cleaner-fulcrum O; i, scraping-plummet; j, counter-balance-weight connected by chain with cleaning-plummet; k, Figs. 10 and 11, lower and coarser portion of regenerator flue-work; l, 80 lintels at the top of this portion of the regenerator; m, upper and finer portion of regenerator flue-work; n, a spar used in place of jet-pipe N when the flue-scraper is used.

In the construction illustrated in Fig. 1 is 85 represented a three-pass stove of the vertical regenerative fire-brick type, the gas igniting at the foot of the combustion-chamber A, rising to the top of the same, descending through the regenerator-flues B to the chamber at the 90 foot of the regenerator, thence ascending through the regenerator-flues C and out through the chimney-connection at the top of the stove. When the stove has been heated, the various valves are manipulated as usual, 95 and the blast from the cold-blast main passes through the stove in a direction the reverse of that just mentioned for the heating medium. I support the regenerator-flues without the use of piers, and without involving arches 100 limited in thickness by the thickness of the walls of the regenerator-flues. The vertical

regenerator-walls are formed, as usual, with a thickness at the base portion of about four and a half inches. There are two sets of these walls, as usual, at right angles to each other, 5 producing the usual flues. I arrange the arches *P*, of greater thickness than the walls directly over them, under some of the walls of one of these sets, the arches being under alternate walls or under the third, or fourth, or 10 fifth wall, as desired, Fig. 6 illustrating at one point one wall between arched walls and at another point three walls between arched walls. The walls crossing this set of walls are supported on lintels *Q*, which rest upon the 15 arches, and the intermediate walls of the first-mentioned set are also supported by these lintels, the wall-work being, of course, all built in and bonded together. I thus secure a reliable regenerator structure based upon 20 arches of substantial width which do not clog the base of the regenerator.

In Fig. 1 and its cross-sections I represent, for simplicity's sake, the regenerator-flues as being of uniform size and arrangement from 25 top to bottom. It is desirable that the heating-surface of these flues be increased without decreasing the strength of the base of the regenerator. In Figs. 10 and 11 I illustrate my manner of so doing. I make the 30 arches *P*, about nine inches thick, and I construct the flues *k* over them with walls four and a half inches thick, carrying these flues up, say, ten or fifteen feet. At this point I span these flues by lintels *l*, and from them I 35 carry upward the smaller flues *m* with walls, say half as thick as the walls below. By this means each lower flue *k* becomes divided into four smaller flues, *m*, as will be clearly understood from Fig. 11, and at the same time 40 the base of the structure is formed with thick and substantial walls. This subdivision of the walls may take place at any desired point in the height of the flues, and it may be effected more than once, if desired. The separating-wall *R* is subjected to much greater 45 heat upon one side than upon the other, and it is common to employ a higher grade of fire-brick in the construction of the face which becomes the most highly heated. Differential 50 expansion results from the difference in the heat of the two faces and from the difference in the grade of fire-brick employed in the faces, and it is often extremely difficult to secure durability in the wall. I overcome 55 this difficulty by splitting the wall, as shown, thus virtually forming a stove in two longitudinal parts, which may expand independent of each other. The wall is built up close, but not bonded. The split of the wall may, if 60 desired, extend clear to its base; but I prefer to begin it at a point from ten to twenty feet above its base. I thereby secure the benefit of a thick wall at the base, and the substantial equal temperature at this point permits me to avail myself of this benefit.

Another feature of my invention relates to a means for securing a more uniform heating

in the regenerator and for avoiding gas deposits at the top of the down-pass *B*. If the products of combustion pass up the combustion-chamber, and then down and up through the regenerator, the final pass of the regenerator will not be heated as much as desired, and the products will leave deposits at the top of the down-pass *B*. To avoid both these faults 70 I cause a portion of the products of combustion to take a short path through flue *M*, Figs. 1 and 4, to the foot of the regenerator, whence they move rapidly upward and subject the final pass of the regenerator to the 75 action of the products of combustion, carrying their maximum sensible heat. This method must not be confused with a plan by which gas and air are admitted at the foot of the regenerator and there ignited. In 80 my plan the combustion takes place in the combustion-chamber, and it is a portion of the products of this combustion which I cause to pass immediately to the foot of the regenerator. The powerful draft through the last 85 pass of the regenerator draws these products rapidly in and takes from the current, which usually moves up the combustion-chamber, a large portion of the deposits which usually 90 lodge at the top of the first down-pass. The 95 flue by which these products find their short path taps the combustion-chamber, as shown in Fig. 1, at a point just above the point of ignition of the gas—that is, the point where the 100 gas and air of combustion combine—and has its outlet at the foot of the final up-pass of the regenerator, the outlet being controlled by a slide-plug operated, in the construction illustrated, by a handle outside the stove, whereby this flue can be closed when the stove is 105 under blast. The flue may be in or against the wall of the stove, or disposed centrally, or both, as shown in Fig. 4. The valve consists of a plug sliding in the flue and serving to plug the flue and cut off the outlet-port, or to 110 cut off the flue and to plug the outlet-port. This flue carries the deposits before mentioned to the chamber at the foot of the regenerator, and the cleaning-hole *X* permits the cleaning 115 of the chamber and flue. There is the usual expansion-space, sometimes packed with filling, between the walls of the stove and the metal shell, and the gas is liable at times to work its way into these spaces. In order to prevent the chimney exerting any drafts upon 120 these spaces, I arrange for a tight seal at the chimney-outlet from the top of the regenerator. The chimney or chimney-connection *D* rises from the metal roof, and from the brick-work of the roof of the final pass of the regenerator a brick nozzle, *T*, rises sufficiently to enter the chimney-connection, in which it fits 125 neatly, thus forming a perfect seal against any connection between the chimney and the jacket-space. The chimney-connection, where it engages the nozzle, may slip somewhat, when necessary, thus preventing the nozzle 130 being broken by differential movement of the brick-work and the metal-work of the roof.

The nozzle may be a simple brick curbing rising from the brick roof; but I much prefer the construction illustrated in Figs. 1 and 7, especially where the brick roof of the stove is arched, as is usually the case. I leave in the brick-roof work a circular hole with some taper, and I form the nozzle S of a series of segmental bricks, Y, reaching endwise from the chimney-connection in the metal roof down into the hole in the brick roof and fitting the taper hole therein. The hole in the brick roof in which this nozzle is thus seated I form by means of special brick Z, which gives the tapering circular form to the opening, and which gives a square bearing for the bricks of the roof, which abut against these special bricks. This construction prevents the strain of the roof-work distorting the nozzle-seat, and it prevents the strain due to the nozzle-seat from 20 distorting the roof-work.

Another feature of my invention relates to the manner of preventing damage to the hot-blast valve and gas-valve by the premature burning of gases near them, while at the same time securing the economical advantages of a single stove-connection serving for a gas-inlet and a hot-blast outlet. The pipe E, Fig. 1, communicates with the stove at the base of the combustion-chamber. It leads to the hot-blast main, and is provided with hot-blast valve L. The gas is, as usual, also admitted to the stove through the pipe E. The hot-blast valve is liable at all times to leak a trifle, and therefore allow more or less air to move back into the pipe E and mingle with the incoming gas, which thus ignites, thereby damaging the hot-blast valve and the gas-valve. I obviate this difficulty to a great extent by tapping the gas-pipe E as closely as possible to the side of the stove, whereby the least possible resistance is offered to the immediate entrance of the gas to the stove. The light pressure of the leaking air, together with the draft of the stove, will thus serve to draw the gas through its single free short channel into the combustion-chamber before it ignites. The gas-branch G, which taps onto the pipe E, I arrange horizontally for a short distance, and then lead it upward. I place the gas-valve F in its vertical portion, where I also place the gas-damper, should such be used in connection with the main gas-valve. I also turn the pipe E upward, and in this vertical portion I place the hot-blast valve L. I thus secure a volume of gas uncombined with air directly underneath the gas-valve, whereby the tendency of the gas-valve to be burned is lessened, and whereby I am enabled to dispense with any artificial cooling of the gas-valve.

Another feature of my invention relates to the construction and relative arrangement of the inlets for the gas and air of combustion. The gas enters the combustion-chamber at H from the pipe E, the same pipe serving as the outlet for the hot-blast, as before mentioned. Immediately below the gas-inlet H, and at the foot of the combustion-chamber, I place the

inlet I for the air of combustion, both the inlets having a broad side flare, as indicated in Figs. 4 and 5. I am enabled by this disposition and arrangement of but two openings upon what is known as the "hot side" of the stove to effect the commingling and diffusion of the air and gas more perfectly than by means of a number of openings into the stove, as usually employed. The inlet I for the air of combustion has a screw-valve, K, by which the supply of air is regulated, and the seat of this valve forms a door, J, which is hinged to the opening I. This arrangement and disposition enable this one opening to serve for the supply and regulation of the air of combustion, for the purposes of cleaning the base of the combustion-chamber, and as a means for firing the stove with solid fuel.

The drawings exhibit means for cleaning the stove and for cooling the valves. These features are not described at length in the specification, as they are not claimed herein, and may form the subject of other patents.

In connection with the described splitting of the wall R, it should be stated that a construction has been proposed in which two stoves stand closely side by side, the metal shells of the contiguous portions almost touching each other. Again, the combustion-chamber, instead of being included directly in the stove, has been in the form of a conduit standing parallel with the stove, the metal shells in the two portions being, as before, almost in contact. In either of these cases it might be said that a wall divides two chambers, and that such wall is of a dual character. It will be at once understood, however, that such constructions do not present to any degree the characteristic of the split wall referred to. The two walls in the constructions alluded to are entirely independent of each other. They pertain to two independent structures. There are two layers of the shell-metal between them, and there is a space between the two layers of the metal. The contiguity of the two walls is a mere incident to the parallelism of the two separate structures to which the walls belong. Furthermore, the two structures have circular cross-sections, and are contiguous only at the point where the two circles approach each other. In these constructions one wall, whether split or not split, would not answer the purpose for which these walls are employed. In my construction a single wall would answer fully the purpose of a mere dividing-wall, the split of the wall being a feature introduced for the purpose specified—a purpose which would not be performed by two independent walls having a passage between them, through which either cooling-air or heating-gas might pass.

In connection with the hot-product flue of my construction it may be well to mention that in addition to the gas-flue which feeds the base of the combustion-chamber it has been proposed to supply also an inlet from the gas-main to the base of the regenerator, the

gas which is admitted at the base of the regenerator being supplied with air of combustion at that point, thereby causing the base of the regenerator to serve as a second combustion-chamber. It has also been proposed to admit gas and air of combustion at various points in the regenerator. In my construction the combustion takes place entirely within the combustion-chamber; but I divert a portion 10 of the hot products of the combustion immediately to the base of the regenerator.

In connection with the description of my peculiar arrangement for connecting the final uptake of the regenerator with the chimney, 15 it may be well to state that it has been proposed that the metal roof of the stove shall be free from contact with the brick roof, and that the brick-work of the roof should be built upward to form a lining for the chimney. This 20 is really a common and obvious method of connecting the chimney-lining with the brick-work at the roof of the stove; but unfortunately no provision was made by which the metal of the chimney could move, or the roof move without causing also a movement of the chimney-lining, and if the movement of the brick-work of the stove was not coincident with the movement of the metal work (and the movements never do coincide) the tendency 25 was to break loose the juncture between the chimney-lining and the brick-work of the roof. In my construction the brick roof of the stove is provided with a nozzle which enters the base of the metal chimney a trifling distance, 30 and is at liberty to slide therein, thus permitting the metal work and the brick-work to partake of independent motions without doing damage.

It has been proposed in topping out chimneys for general purposes to set a bushing in 40 the top of the chimney, and to set a prolongation of the chimney over the bushing, the bushing thus forming a nozzle, which projects upward into the prolongation. In such case 45 there was no differential expansion of brick-work and metal to contend with, and the construction was not adapted to meet the difficulties of such conditions, as the prolongation referred to was supported directly by the chimney, and was necessarily bound to rise and fall with it.

In connection with the arrangement of the gas-inlet, &c., it should be stated that the gas-pipe has heretofore been tapped into the hot-blast main at a point between the stove and the hot-blast valve, air for combustion being admitted to the combustion-chamber of the stove at a point some distance above the inlet, thus avoiding combustion low down in the 55 combustion-chamber, and at the same time losing the benefits of a portion of the length of the combustion-chamber. Air for combustion has been admitted below the common opening; but the disposition of the gas and 60 hot-blast connections have been such as to re-

sult in a rapid destruction of the hot blast valve.

In connection with the split separating-wall acknowledgment should be made of the existence of contacting-walls forming the inner and outer lining of hot-blast stoves and of contiguous arches, which touch each other at their inner crowns. 70

I claim as my invention—

1. In a hot-blast stove, the combination of 75 a supporting structure at the base of the regenerator, chord-walls and ordinate walls rising from the same and forming flues reaching a portion of the height of the regenerator, thinner continuations of said walls to the top 80 of the regenerator, and thin chord and ordinate walls interposed between said continuations and serving to increase the number and decrease the area of the flues in the upper portion of the regenerator. 85

2. In a hot-blast stove, the separating-wall R, split or formed in two thicknesses independent of but in contact with each other, substantially as and for the purpose set forth.

3. In a hot-blast stove, the separating-wall 90 R, solid at its base and split or formed in two thicknesses independent of but in contact with each other above the solid portion, substantially as and for the purpose set forth.

4. The combination of the combustion-chamber, the regenerator, and one or more flues leading from the combustion-chamber to the foot of the uptake portion of the regenerator, for the purpose of forming a short path for a portion of the hot products of combustion 100 from the combustion-chamber to the regenerator. 95

5. The combination of the combustion-chamber, the regenerator, and the descending flue M from the combustion-chamber to the base 105 of the regenerator, for the purpose of carrying hot products of combustion to the base of the regenerator and bringing gas-deposits into the chamber below the regenerator.

6. The combination of the combustion-chamber, the regenerator, the descending hot-product flue M, and the sliding plug-valve provided with a handle exterior to the stove. 110

7. The combination of the combustion-chamber, the regenerator, the descending flue M for 115 hot products and gas deposits, and the cleaning-opening X in the wall of the stove.

8. In a hot-blast stove, the combination, substantially as set forth, of the brick-work and the brick roof of the stove, a metal shell and 120 metal roof inclosing the same, a metal chimney-connection joining and supported by the metal roof, and a nozzle rising from the brick roof and entering the metal chimney-connection a short distance and forming a slip-joint 125 therein.

9. In a hot-blast stove, the combination, substantially as set forth, of the brick-work and the brick roof of the stove, the metal shell and 130 roof inclosing the same, a metal chimney-con-

nection joining and supported by the metal roof, and a nozzle seating in a tapering opening in the brick roof and projecting a short distance into the chimney-connection and forming a slip-joint therein.

10. In a hot-blast stove, the combination of the brick-work and brick roof of the stove, a metal shell and roof inclosing the same, a metal chimney-connection joined to and supported by the metal roof, and a nozzle consisting of segmental brick with a vertical sectional contour parallel at one end and wedge-shaped at the other end, forming a tapering seating in the brick roof of the stove, and a short parallel 15 slip-joint in the metal chimney-connection.

11. The combination, substantially as set

forth, of the pipe E, projecting outward from near the base of the combustion-chamber and into communication with the hot-blast main, a hot-blast valve between the stove and hot- 20 blast main, a gas-pipe tapping said pipe between such valve and the stove, an opening into the combustion-chamber directly below the opening by which said pipe communicates with the stove, and a valve at said opening for 25 controlling the admission of air of combustion and for closing such opening when the stove is under blast.
